UNITED STATES PATENT OFFICE.

JOHN H. WARNER AND HOWARD S. SMITH, OF DAYTON, OHIO.

DESIGN FOR AN AUTOMOBILE-RADIATOR ATTACHMENT.

51,402.

Specification for Design.

Patented Oct. 16, 1917.

Application filed August 6, 1917. Serial No. 184,760. Term of patent 3½ years.

To all whom it may concern:

Be it known that we, JOHN H. WARNER and HOWARD S. SMITH, citizens of the United States, residing at Dayton, in the county of Montgomery and State of Ohio, have invented a new, original, and ornamental Design for an Automobile-Radiator Attachment, of which the following is a specification, reference being had to the accompanying drawing, forming part thereof.

The figure is a front view of our new design.

We claim:

The ornamental design for an automobile radiator attachment, as shown.

JOHN H. WARNER,
HOWARD S. SMITH.

Witnesses:

WALTER V. SNYDER,
PHICO G. BURNHAM.
